UNITED STATES PATENT OFFICE

JOHN WENZEL, OF FOLEY, ALABAMA

DESIGN FOR AN AUTOMOBILE IDENTIFICATION PLATE

Application filed June 15, 1931. Serial No. 40,214. Term of patent 7 years.

To all whom it may concern:

Be it known that I, JOHN WENZEL, a citizen of the United States of America, residing at Foley, in the county of Baldwin and State of Alabama, have invented a new, original, and ornamental Design for an Automobile Identification Plate, of which the following is a specification, reference being had to the accompanying drawings forming a part thereof.

new design.

I claim:

The ornamental design for an automobile identification plate as shown.

JOHN WENZEL.
